STACKING DEVICE

Edmund N. Neckel, Cincinnati, Ohio, assignor to
 The American Laundry Machinery Company,
 Norwood, Ohio, a corporation of Ohio

Application October 16, 1939, Serial No. 299,621

4 Claims. (Cl. 271—87)

This invention relates to machines for stacking flat folded articles. While the mechanism is usable for any kind of flat articles, it is more particularly adapted for fabric articles which have been ironed and folded, and more especially those fabric articles which are comparatively large in area and are more or less soft, flimsy or limp, either on account of the texture or character of the material itself or the manner in which it has been dried. Diapers which have been tumbler dried or otherwise air dried are in this class. They do not have either the glaze-like finish or the body stiffness characteristic of other work such as napkins or table cloths or even handkerchiefs.

One object of the invention is to provide an improved stacking machine which stacks the articles by supplying them to the bottom of the pile and properly supports them, even though large and flimsy, while so doing.

A further object is to provide an improved machine of this kind which stacks from the bottom upwardly in a manner to minimize the amount of lift of the pile while adding a new article thereto.

A further object is to provide an improved stacking machine in which the supporting plates for the pile are withdrawn horizontally while the lifting plate raises the next article into proper position for addition to the pile.

Still another object is to provide an improved machine of this kind in which the movement of the stack supporting plates is produced in timed relation with the motion of the lifting plate while elevating the next article.

Another object is generally to improve the mechanism for actuating the several plates and other operating parts to simplify the same and secure the most efficient and properly coordinated operation.

Further objects of the invention are in part obvious and in part will appear more in detail hereinafter.

In the drawings, which represent one suitable embodiment of the invention,

Fig. 1 is a plan view illustrating the stacking mechanism in detail and the casing of a folding machine with which it may be associated;

Fig. 2 is a rear elevation;

Fig. 3 is a fragmental elevation, from the right in Fig. 2, illustrating the stacking mechanism in normal position ready to receive an article to be stacked.

Fig. 4 illustrates the same parts in their re-

spective positions when the lifting plate nears the plane of the supporting wings.

Fig. 5 is a similar view, illustrating the parts when the lifting plate has passed above the plane of the wings, which have then returned to their supporting position.

Fig. 6 is a sectional plan view on the line 6—6, Fig. 4, and

Fig. 7 is a detail sectional view on the line 7—7, Fig. 6.

While the stacking mechanism of the present invention may be used by itself, with the work fed to it by hand or machine, or may be associated with any other cooperating machine, such as an ironing machine or any type of folding machine, the drawings, for purposes of illustration, show stacking mechanism combined with a folding machine, all parts of each thereof being of the same form shown and described in an application for folding machine, Serial Number 299,617, filed of even date herewith by George W. Johnson, to which reference may be had for further illustration or description if desirable or necessary.

The folding machine is illustrated generally at 1. It requires no detailed description except to say that articles to be folded, such as diapers are introduced to it by applying them flatwise to the work receiving belts 2, which feed them to folding devices which produce two folds, one longitudinal and the other transverse, and deliver the twice-folded four-ply article to a curved plate 3 down which they slide by gravity toward and into the stacking mechanism now to be described.

Plate 3 extends into the stacking mechanism, at the far end of which its edge is turned up to form a stop 4, which stops the article and properly positions it for registration with the lifting plate 5 of the stacking mechanism.

The lifting plate, as shown in Fig. 1, is provided with a plurality of laterally extending fingers 6, lying in recesses or slots in that portion of the plate 3 which extends through the stacking device. In other words, that area of the plate 3 which lies within the stacking device is recessed or cut away with an opening of the same shape as the lifting plate 5, so that when plate 5 lies at the same level as the horizontal portion of plate 3, the two together form a continuous plate along which the article travels to its final position against the stop 4. When in such position, if the lifting plate rises it elevates the article with it.

Above the plates 3 and 5, in the stacking device, are a pair of like stack supporting plates,

respectively marked 7, 8, each provided with inwardly extending lateral fingers 9 which register with the spaces between the fingers 6 of the lifting plate 5, so that free movement of the lifting plate 5 above the stack supporting plates 7, 8 when in their stack supporting position shown in Fig. 3, is possible and is permitted.

The two stack supporting plates 7, 8, have lateral movement toward and from each other, preferably in timed relation with the upward movement of the lifting plate 5, so that as an article upon the plate 5 is lifted with it, the side plates 7, 8, are withdrawn to permit free unobstructed further advance of the article to a level above plates 7, 8, whereupon plates 7, 8 automatically move inwardly to receive and support the stack as a whole, when the lifting plate descends. The construction and arrangement for this purpose is as follows:

20 Plates 7, 8 at each end are provided with sleeve portions 10 mounted to slide upon rods 11, the two plates being biased toward each other by tension springs 12.

Lifting plate 5 is provided with a depending 25 operating post 13 which has secured to it a rack 14 meshing with a pinion 15 on a shaft 16, Figs. 2 and 6. Said shaft has pinned to it a lever 17 provided with a pawl 18 normally held in engagement with a ratchet wheel 19, secured to a 30 sleeve 20 in which the shaft 16 is journaled. Also secured to the sleeve is a lever member 21 connected by a link 22 to a sleeve 10 carried by plate 7.

Also secured to the sleeve 20 is a gear 23 meshing with a gear 24 on a stub shaft 25 provided with an arm 26 corresponding to arm 21 and similarly connected by a link 27 to the other stack supporting plate 8.

The depending post 13 of the lifting plate 5, at 40 its lower end, is provided with a roller 28 for engagement with a pad or plate 29 on one arm of a lever 30 actuated by suitable mechanism, including a link 31.

When a twice folded article reaches and is received by and properly presented on the lifting plate, lever 30 is operated and the plate is elevated, the upward movement thereof, through the rack 14 and pinion 15, rotating shaft 16 and turning lever 17, which through its pawl 18 rotates the ratchet wheel 19 and sleeve 20, and through the geared connection 23, 24 causes the two plates 7, 8 to move outwardly upon the rods 11 against the tension of springs 12. Such movement of the plates takes place while the lifting plate 5 is moving from the position shown in Fig. 3 to that shown in Fig. 4. Continued movement of the lifting plate elevates the freshly folded article above the level of the supporting plates 7, 8. When the lifting plate reaches the 60 elevation shown in Fig. 5 the pawl 18 has reached a raised portion on a cam member 18a attached to the frame, which cams the pawl to the out of engagement position with the ratchet wheel, and the springs 12 thereupon become effective to re-

turn the plates 7, 8, links 22 and 27, the levers 21, 26 to their original inward positions, with the tongues of plates 7, 8 lying beneath the side edges of the article. Therefore, when the lifting plate 5 is lowered by reverse movement of lever 30 the 5 article and the rest of the pile above it are retained by plates 7, 8 and rest thereon. Suitable guiding posts 33 for the stack may be supported upon the frame or brackets attached thereto.

The invention provides simple mechanism of 10 improved form, involving minimum stack lift and securing proper timed relation between the lifting and supporting plates as well as other advantages that will be apparent to those skilled in the art.

What I claim is:

1. Stacking mechanism of the character described, comprising a vertically movable lifting plate upon which an article may be fed to be stacked, side plates, horizontally movable slides supporting the same, two interengaging pinions, 20 one for each slide, operating connections from each pinion to its slide, and means operatively connected to said lifting plate and to one of said pinions for actuating the same.

2. Stacking mechanism of the character de- 25 scribed, comprising a vertically movable lifting plate upon which an article may be fed to be stacked, side plates, horizontally movable slides supporting the same, two interengaging pinions, 30 one for each slide, operating connections from each pinion to its slide, and means operatively connected to said lifting plate and to one of said pinions for actuating the same, said means including a pawl and ratchet connection for operating the said pinion, and means for uncoupling 35 said pawl and ratchet.

3. Stacking mechanism of the character de- 40 scribed, comprising a vertically movable lifting plate upon which an article may be fed to be stacked, side plates, horizontally movable slides 45 supporting the same, two interengaging pinions, one for each slide, operating connections from each pinion to its slide, and means operatively connected to said lifting plate and to one of said pinions for actuating the same, said means in- 50 cluding a pawl and ratchet connection for operating the said pinion, means biasing said slides to stack supporting position, and means arranged upon elevation of said lifting plate to uncouple the pawl and ratchet to thereby release the slides for movement to stack supporting position.

4. Stacking mechanism of the character de- 55 scribed comprising a vertically movable lifting plate upon which an article may be fed to be stacked, side plates for supporting said stack, horizontally movable slides controlling said plates, drive means for moving said slides outwardly operable by movement of said plate upwardly, means for disconnecting said drive means by movement of said plate to an upper limit, and 60 energy storing means for returning said slides inwardly upon disconnection of said drive means.

EDMUND N. NECKEL.
